UNITED STATES PATENT OFFICE.

GEORGE S. CLASON, OF DENVER, COLORADO.

RAZOR-BLADE HANDLE.

1,360,888.

Specification of Letters Patent. Patented Nov. 30, 1920.

Application filed May 13, 1919. Serial No. 296,758.

To all whom it may concern:

Be it known that I, GEORGE S. CLASON, a citizen of the United States, residing in the city and county of Denver and State 5 of Colorado, have invented a new and useful Razor-Blade Handle, of which the following is a specification.

My invention relates to improvements in handles for holding razor blades while the 10 same are being sharpened. The object of my improvement is to provide a positive method of clamping the razor blade in the handle with a single movement of the operating member.

I attain this object by the mechanism 15 illustrated in the accompanying drawing, in which—

Figure 1 is a general view showing the 20 razor blade clamped in position to be sharpened; Fig. 2 is an end view; Fig. 3, side view of the handle member with the operating member removed; Fig. 4, an end view of the handle; Fig. 5, a side view of the operating member; Fig. 6, an end view of 25 the operating member.

Similar letters refer to similar parts throughout the several views.

A represents the handle. B represents the 30 sliding or clamping member. Forming a part of the handle A, are the grippers D, opposing each other and normally at a slight distance apart. The grippers are attached to the handle by a narrow portion E, permitting them to be sprung together by a 35 light pressure.

The operating member B comprises a body portion formed to fit over the handle A, an extension F, and operating lug G, a stop H and the extensions J. J. in opposing 40 pairs. In the extensions J. J. are depressions K, representing rounded projections on the under side of said extensions.

To open the grippers, the operating member should be pushed along the handle until 45 the obstructions K. K. slide off the grippers D. D. This permits the grippers to assume their normal position a slight distance apart. In such position the razor blade can

be inserted. By pulling back the operating member B, the obstructions K. K. press 50 against the grippers D. D. and clamp them tightly against the blade.

My invention can be made from any suitable material, preferably sheet metal that can be stamped into the required shapes and 55 bent into the required forms.

I claim:

1. In a razor blade holder, a handle member carrying longitudinally spaced opposed gripping members normally standing apart, 60 a sliding member operating along the handle member and adapted to close the gripping members or permit them to open as the same is moved back and forth.

2. In a razor blade holder, in combination, a handle, longitudinally spaced opposed gripping members carried thereby and normally standing apart, a slide member upon the handle and means carried by the slide member for forcing the gripping 70 members together by sliding movement of the slide member.

3. In a razor blade holder, in combination, a handle, longitudinally spaced opposed gripping members carried thereby 75 and normally standing apart, a slide member upon the handle, longitudinally spaced members carried by the slide member for forcing the gripping members toward each other or releasing them to normal position 80 by movement of the slide.

4. In a razor blade holder, in combination, a handle, longitudinally spaced opposed gripping members carried thereby and normally standing apart, a slide member upon the handle and spaced gripping members carried by the slide member for forcing the gripping members on the handle toward each other or releasing them to normal position by movement of the slide member 85 along the handle and without removal of the slide member from the handle.

GEORGE S. CLASON.
